SIGNALING CIRCUIT

Harold Olaf Peterson and Martin Katzin, Riverhead, N. Y., assignors to Radio Corporation of America, a corporation of Delaware

Original application October 26, 1933, Serial No. 695,254. Divided and this application August 28, 1936, Serial No. 98,266

16 Claims. (Cl. 250—20)

This invention relates to the art of signaling and more particularly to the art of modulation and demodulation of carrier oscillations by means of thermionic tubes, and more specifically to the methods for modulating and demodulating carrier frequencies which employ multi-grid tubes. This application is a division of our United States application #695,254, filed October 26, 1933, now Patent #2,103,869, issued December 28, 1937. The invention makes possible efficient and complete linear demodulation of a signal modulated carrier wave. In this demodulation spurious responses known as harmonic points are eliminated. The method of demodulation is particularly applicable to receivers of the heterodyne type.

Demodulation systems of the heterodyne type known heretofore in some cases do not produce linear demodulation and such systems may respond to interfering signals as well as the desired signal if the interfering signal is at a frequency separated from the local frequency by a difference frequency equal to the beat frequency. Or the desired signal may appear at two different settings of the tuning elements.

An object of the present invention is to accomplish linear and complete demodulation of a signal modulated carrier frequency by employing thermionic tubes having a multiplicity of control grids or electrodes, applying the signal modulated carrier frequency oscillations to one of the grids and the local oscillations to a plurality of grids in such relative amounts and phases as to result in substantially linear demodulation by the heterodyne method free of interfering signals and image frequencies.

In a modification the signal carrying modulated wave may be applied to a plurality of the grids in certain relative amounts and phases, while the local oscillations may be applied to a single grid.

In a further modification the wave to be demodulated is applied in the desired phase relation to a plurality of grids of a demodulator that reduces the signal without the use of local oscillations.

The invention has, as required by law, been pointed out with particularity in the claims appended hereto.

The method and mode of operation of the same will be best understood from the specification and therefrom when read in connection with the attached drawings, throughout which like reference characters indicate like parts, and in which:

Figure 1 shows schematically a demodulator including features of the present invention;

Figures 2a and 2b are respectively, a wiring

diagram showing the application of practical potentials, and curves derived by operation of the tube of 2a under certain conditions;

Figure 3 is a modification of the arrangement of Figure 1;

Figure 4 illustrates the manner in which the principles of the present invention is applied to demodulation circuits of the non-heterodyne type; while,

Figure 5 is a curve illustrating the operation of the device of Figure 4.

The present invention may best be described by reference to the drawings of Figures 1, 2a and 2b.

Figure 1 shows one specific embodiment of the invention in which a complete telephony receiver is represented. Referring to Figure 1, A is a thermionic tube with which the associated input circuit 5 coupled to aerial 6 forms a conventional signal wave amplifying circuit wherein wave energy modulated in accordance with signals is intercepted by 6, induced in 5, amplified in A and appears in the tuned circuit TC connected with the anode 7 of A. The tuned circuit TC includes an inductance 13' forming the primary winding of a transformer having a secondary winding 13. Coupling coil 13 serves to transfer energy from the amplifier A to the innermost grid 29 of the four-grid thermionic tube 21, which grid is biased to a suitable negative potential with respect to cathode 16 by means of a potential source or battery 14. The grid 18 is bypassed for radio-frequency by means of condenser 22 and choke coil 25. This grid forms a shield between the grid 29 and the input circuits connected therewith and the other tube elements and circuits. Grid 18 is maintained at suitable positive direct-current potential by means of battery 32, grid 19 is shown as being maintained at suitable negative potential with respect to the cathode 16 by means of battery 33, while grid 19' is maintained at a suitable positive potential relative to the cathode 16 by source 39'. Grid 19 may be the usual suppressor grid, 18 the usual screen grid, 19' an auxiliary grid electrode between shield grid 18 and suppressor grid 19, and 29 the usual control grid of a tube. Voltage variations of beat frequency, generated by the oscillator O comprising tube T and its regenerative circuits, are applied to the two grids 19 and 19' by coupling between inductance I in the oscillator circuit and inductance I' coupled to grids 19 and 19'.

By means of this coupling beating voltages are applied to both grids 19 and 19' in phase. Plate 20 of tube 21 is connected by a choke in- 55

ductance 34 and radio-frequency by-pass condenser 35 to an intermediate frequency amplifier 50 in which the wave energy of intermediate frequency resulting from the beating action in tube 20 appears for subsequent utilization.

The operation of the demodulator tube 21 in Figure 1 may best be described with reference to Figures 2a and 2b.

The tube T₁ of Figure 2a represents the tube 21 of Figure 1 and shows the connection of the various voltages to the several electrodes of the tube including grids 29, 19' and 19 represented in Fig. 2a as grids G₁, G₂ and G₃, respectively. The curves of Figure 2b represent the transconductance between grid G₁ and plate P for various operating potentials on the several electrodes. Since the output voltage produced across the load in the plate circuit of the tube is proportional to the transconductance between the input electrode and the plate, the curves of Figure 2b also represent the voltage output obtainable under the several conditions.

Curve A of Figure 2b shows the variation of transconductance with E_{G2}, the voltage between grid G₂ and cathode K, showing that considerable distortion would be entailed by applying modulating voltage to grid G₂. Similarly curve B, showing transconductance versus E_{G3}, the voltage between grid G₃ and cathode K, shows that high modulation percentages would be subject to considerable distortion.

Curve C shows the improvement obtained by varying the potentials of G₂ and G₃ simultaneously by equal amounts. The result is that the curved portion near the cut-off point is reduced and the cut-off made sharper. The reason for this is that as G₃ is made more negative, G₂ is simultaneously made less positive, and thus assists in the reduction of transconductance. For composite modulation corresponding to curve C, operation at the direct current electrode potentials corresponding to point a on the curve would be most suitable. As a result, the composite curve C would allow higher modulation percentages without distortion than would curve B.

The operation of this device is not restricted to simultaneous variation of the two grid potentials in equal amounts, as described in the specific embodiment above. The basic principle is to vary simultaneously the potentials of a plurality of electrodes in the proper proportions to obtain linear operation and therefore minimum distortion. One example is shown by curve D of Figure 2b, in which the potential of grid G₂ is changed by twice the amount as G₃. Operation at the direct current potentials corresponding to point b of this curve would allow substantially complete modulation to be obtained with very little distortion.

In the modification illustrated in Figure 1, the grids 19' and 19 are moved (potentially) by the beating or modulating potentials in the same direction.

The upper end of curves C and D in Figure 2b, which remain curved, but are not utilized as part of the modulation characteristic by virtue of the selection of the direct current potentials of the electrodes to correspond to points a and b, respectively, may be further straightened by connecting a negative resistance device in series with electrode G₂, so that as the current drawn by this electrode increases due to a positive excursion of the modulating voltage, the voltage applied between electrode G₂ and cathode K will be still further augmented by the negative resistance de-

vice, thus still further increasing the transconductance. This would allow moving points a and b higher upon the curve and thus give greater modulated output from the device.

Although the specific embodiment of the modulation circuit described above is to be used with a four-grid tube, it is understood that the principles of this invention are applicable to a tube of any number of electrodes in which linear modulation is obtained by simultaneous variation of the potentials of a plurality of electrodes at the modulation frequency.

Returning to the operation of Figure 1, tube A and associated circuits form a stage of radio frequency amplification. The anode circuit of tube A may be connected with a tunable circuit TC including an inductance 13' coupled with an inductance 13 connected with the control grid 29 of a tube 21, which in this case acts as a demodulator tube. O is an oscillator including a thermionic tube T having output and input electrodes coupled, as shown, to an oscillation producing circuit including frequency determining means. The oscillation producing circuit includes an inductance I coupled, as shown, to an additional inductance I'. The inductance I supplies energy from the heterodyne oscillator O by way of inductance I' to the grids 19 and 19' of tube 21. In this case the grid 18 serves as a shield between the signal circuits and the local heterodyne oscillator O. The demodulated signals appear in the anode circuit including the choke 41' and capacity 40' and may be impressed on any utilization circuit by way of an intermediate frequency amplifier 50.

The use of two grids 19 and 19' fed with energy from the heterodyning frequency oscillator provides a linear operating characteristic as described above. This results in improved demodulation characteristics in the elimination of spurious responses known as "harmonic points". A brief explanation of the origin of these spurious responses will show how the use of the multi-grid modulation principle helps to eliminate them.

Suppose we have a superheterodyne receiver 45 whose intermediate frequency amplifier operates at a frequency of 100 kilocycles. Let us tune this receiver to receive a signal S whose frequency is 10,000 kilocycles. The heterodyne oscillator will therefore be set at a frequency B 50 of either 9900 kilocycles or 10,100; let us choose 10,100 kilocycles. If, in addition to the desired signal S, there is also present a signal (undesired) whose frequency I is 10,200 kilocycles, this second signal will also beat with the heterodyne 55 oscillator frequency to form a frequency of 100 kilocycles. This undesired signal I is called the image frequency and it is primarily for the purpose of eliminating this image that radio frequency amplification (and selectivity) is added 60 ahead of the heterodyne demodulator.

Now suppose, that, in addition to the desired signal S, the input to the receiver contains a frequency H of 10,050 kilocycles, separated from the heterodyning frequency B by half the intermediate frequency. If the signal grid characteristic is not perfectly linear, that is, if the signal grid to plate transconductance versus signal grid voltage is not a straight line, and similarly if the heterodyne frequency grid characteristic is not linear, 70 then there will appear a number of frequencies in the plate circuit among which is one, 2 (H-B), which equals 100 kilocycles. Therefore, the frequency H (10,050 kilocycles) will give rise to interference. Similarly, other interferences will be 75

encountered for frequencies separated from the heterodyning frequency by integral fractions of the intermediate frequency, i. e., $\frac{1}{2}$, $\frac{1}{3}$, $\frac{1}{4}$, $\frac{1}{5}$, . . . etc., of the intermediate frequency. These 5 interferences or spurious responses are known as "harmonic point" responses.

Now if either the signal grid characteristic or the heterodyning grid characteristic is absolutely linear, then these harmonic point responses 10 will not appear. It is to this end that the principle of double grid modulation would prove useful in a superheterodyne receiver. Obviously, either characteristic could be made very nearly linear by using the two grid principle, so that 15 this case would be one where the connections for the signal frequency and heterodyning frequency could be interchanged. Figure 3 shows an arrangement in which the beating oscillations are applied to the grid 29 and the signal 20 carrying oscillations are applied in the desired phase relation on the grids 19 and 19', while 18 serves for shielding purposes.

Also it is evident that the two grid idea could 25 be applied to each frequency so that we would have a five grid demodulator, the middle grid acting as a shield between the two circuits. We have not shown a diagram of this connection, but the extension is obvious.

While the invention has been illustrated as 30 being applicable to heterodyne demodulators in which a four-grid tube is preferably used so that a screening grid may be interposed between the signal modulation carrier receiving circuits and the heterodyne circuits, it will be understood 35 that the invention is also applicable to non-heterodyne demodulation. In such a case a three-grid tube may be used. A signal modulated carrier may be applied to two grids while the inner grid is suitably biased. The biases on 40 the first grids are such that the tube is in the cut-off position when no signal is applied. A circuit of the non-heterodyne type, as, for example, a second detector in a heterodyne circuit, has been shown for purposes of illustration in 45 Figure 4.

While we have shown a three-grid tube in this modification, Figure 4, it is understood that grid 29 and its associated biasing battery may be omitted, thus allowing the principles of this 50 modification to be effected with a two-grid tube.

In Figure 4 the radio frequency amplifier A is coupled by way of its output circuit TC to an inductance 13 which impresses the signal modulated carrier frequency oscillations amplified by 55 A in the desired phase relationship upon the two outer grids 19 and 19'. The inner grid 29 is in this case biased to a suitable potential by a source as shown. The direct current potentials for the grids 19 and 19' respectively are fixed 60 by the direct current sources 39 and 39' connected as shown.

The potential of the sources is so selected that the tube is operated in the cut-off position when no signal is applied. This point is indicated at 65 a in Figure 5 of the drawings.

The linear demodulated oscillations may be fed from the anode circuit including the transformer T_2 to a work circuit directly or by way of additional amplifiers including one or more 70 thermionic tubes 50 connected with the secondary winding of transformer T_2 .

We claim:

1. The method of effecting distortionless demodulation of signal modulated carrier frequency oscillations by means of an electron dis- 75
- charge tube having a control grid electrode, a cathode electrode and a plurality of auxiliary grid-like electrodes which includes the steps of, impressing signal modulated carrier frequency oscillations on said control grid electrode, applying other oscillations substantially in phase to a pair of said auxiliary electrodes, and maintaining the same at different direct current potentials with respect to said cathode, one of said auxiliary grid-like electrodes being maintained at a potential equal to the potential of the other auxiliary electrode plus a constant. 5
2. The method of signaling by means of an electron discharge tube having a cathode electrode and a plurality of grid-like electrodes 10 which includes the steps of, impressing oscillations on one of said grid-like electrodes, applying signal modulated oscillations of different frequency substantially in phase to a pair of said grid-like electrodes and maintaining the same at different direct current potentials with respect to said cathode, one of said pair of grid-like electrodes being maintained at a potential equal to the potential of the other pair of grid-like electrode plus a constant. 15
3. The method of effecting distortionless demodulation of signal modulated carrier frequency oscillations by means of an electron discharge tube having a cathode electrode, and a plurality of grid-like electrodes which includes the steps of, impressing the signal modulated carrier frequency oscillations on one of said grid-like electrodes, applying heterodyning potentials of different amplitude substantially in phase to a pair of said grid-like electrodes, and maintaining the same at different direct current potentials with respect to said cathode, one of said pair of grid-like electrodes being maintained at a potential equal to the potential of the other of said pair of grid-like electrode plus a constant. 20
4. The method of effecting distortionless demodulation of signal modulated carrier frequency oscillations by means of an electron discharge tube having a control grid electrode, a cathode electrode and a plurality of auxiliary 25 electrodes which includes the steps of, maintaining said control grid negative relative to said cathode, impressing signal modulated carrier frequency oscillations substantially in phase on a pair of said auxiliary electrodes, and maintaining the same at different direct current potentials with respect to said cathode, one of said auxiliary electrodes being maintained at twice the potential of the other auxiliary electrode plus a constant. 30
5. The method of effecting distortionless demodulation of signal modulated carrier frequency oscillations by means of an electron discharge tube having a control grid electrode, a cathode electrode and a plurality of auxiliary electrodes 35 which includes the steps of, impressing the signal modulated carrier frequency oscillations on said control grid electrode, applying heterodyning potentials substantially in phase to a pair of said auxiliary electrodes, and maintaining the same at different direct current potentials with respect to said cathode, one of said auxiliary electrodes being maintained at twice the potential of the other auxiliary electrode plus a constant. 40
6. In a signal demodulating system an electron discharge tube having an input electrode coupled with a source of signal modulated carrier frequency oscillations and an output electrode coupled with an output circuit, said tube 45

- having a cathode, a plurality of auxiliary electrodes interposed between said input and output electrodes, a source of heterodyning potentials, separate circuits coupling said source of heterodyning potentials to said auxiliary electrodes for applying heterodyning potentials of different amplitude thereto, and means for maintaining said auxiliary electrodes at different direct current potentials with respect to said cathode.
10. 7. A signal demodulating system comprising an electron discharge tube having a grid electrode, a cathode, an anode coupled with an output circuit, and a plurality of auxiliary electrodes interposed between said grid and anode electrodes, a circuit including a source of potential connecting said grid to said cathode for maintaining said grid negative relative to said cathode, a source of signal modulated oscillations, separate circuits for coupling said source of signal modulated oscillations in phase to said auxiliary electrodes to apply thereto oscillations of different amplitude, and means for maintaining all of said auxiliary electrodes at different direct current potentials with respect to said cathode, one of said auxiliary electrodes being maintained at twice the potential of another auxiliary electrode plus a constant.
8. A signaling device comprising, an electron discharge tube having an anode, a cathode, and a control grid electrode, a circuit for applying signal modulated carrier frequency oscillations to said control grid and cathode, a load circuit connected between said anode and said cathode, an means for effecting linear demodulation of the signal modulated carrier frequency oscillations impressed on said control grid and cathode comprising, a plurality of auxiliary grid-like electrodes interposed between said control grid and anode, circuits for maintaining said auxiliary electrodes at different direct current potentials with respect to said cathode, a source of oscillations, and couplings between said source of oscillations and said last named circuits for impressing oscillations therein in substantially like phase relation.
9. A signaling device comprising, an electron discharge tube having an anode, a cathode, and a control grid electrode, and a plurality of auxiliary electrodes, a circuit for applying oscillations between said control grid and cathode, a load circuit connected between said anode and said cathode, a circuit for applying signal modulated carrier frequency oscillations in phase to a plurality of the auxiliary electrodes and means for maintaining said auxiliary electrodes at different direct current potentials with respect to said cathode.
10. The method of effecting substantially distortionless demodulation of signal modulated carrier frequency oscillations by means of an electron discharge tube having a control electrode, a cathode electrode, and a plurality of auxiliary electrodes which includes the steps of, impressing signal modulated carrier frequency oscillations on said control electrode, applying other oscillations of like frequency and of different amplitude substantially in phase to a pair of said auxiliary electrodes, and maintaining the said pair of auxiliary electrodes at different direct current potentials with respect to said cathode.
11. A method of signaling by means of an electron discharge tube having a cathode electrode, a control electrode and a plurality of auxiliary electrodes which includes the steps of,
- impressing oscillations on said control electrodes, impressing signal modulated oscillations of different amplitude substantially in phase on a pair of said auxiliary electrodes, and maintaining the said pair of auxiliary electrodes at different direct current potentials with respect to said cathode, one electrode of said pair of auxiliary electrodes being maintained at a potential equal to the potential of the other electrode of said pair of auxiliary electrodes plus a constant.
12. The method of effecting substantially distortionless demodulation of signal modulated carrier frequency oscillations by means of an electron discharge tube having a control grid and cathode electrode and a plurality of auxiliary electrodes which includes the steps of, maintaining said control grid negative relative to said cathode, impressing signal modulated carrier frequency oscillations of different amplitude substantially in phase on a pair of said auxiliary electrodes, and maintaining the pair of auxiliary electrodes at different direct current potentials with respect to said cathode.
13. The method of effecting substantially distortionless demodulation of signal modulated carrier frequency oscillations by beating the same with unmodulated oscillations in an electron discharge tube having a cathode, a control grid and a plurality of auxiliary electrodes located at different distances from said cathode which includes the steps of, applying one of said oscillations to said control grid, applying the other of said oscillations substantially in phase to a pair of said auxiliary electrodes, the amplitude of the oscillations applied to the auxiliary electrode of said pair nearest said cathode being materially greater than the amplitude of the oscillations applied to the other electrode of said pair of auxiliary electrodes, and maintaining said auxiliary electrodes at different direct current potentials relative to said cathode.
14. The method of effecting substantially distortionless demodulation of signal modulated carrier frequency oscillations by means of an electron discharge tube having a control grid electrode, a cathode, and two auxiliary electrodes spaced at different distances from said cathode which includes the steps of, impressing signal modulated carrier frequency oscillations on said control grid, applying other oscillations of different amplitude substantially in phase to said pair of auxiliary electrodes, the other oscillations applied to said auxiliary electrode nearest said cathode being of substantially greater amplitude than the other oscillations supplied to the other of said auxiliary electrodes, and maintaining the auxiliary electrodes at different direct current potentials with respect to said cathode.
15. The method of signaling by means of an electron discharge tube having a cathode electrode, a control grid and a plurality of grid-like electrodes spaced at different distances from said cathode which includes the steps of, impressing oscillations on said control grid, impressing signal modulated oscillations of different amplitude substantially in phase on a pair of said grid-like electrodes, the amplitude of the oscillations of different amplitude impressed on the grid-like electrode of said pair nearest the cathode being materially greater than the amplitude of the modulated oscillations impressed on the other electrode of said pair, and maintaining the grid-like electrodes at different direct current potentials relative to the cathode.

16. The method of effecting substantially distortionless demodulation of signal modulated carrier frequency oscillations by means of an electron discharge tube having a control grid, a cathode electrode, and a plurality of auxiliary electrodes located at different distances from the cathode which includes the steps of, maintaining said control grid negative relative to said cathode, impressing signal modulated carrier frequency oscillations on one of said auxiliary electrodes,

impressing signal modulated carrier frequency oscillations of like phase and of materially greater amplitude on another of said auxiliary electrodes located nearer to said cathode than said one auxiliary electrode, and maintaining the auxiliary electrodes at different direct current potentials relative to the cathode.
